UNITED STATES PATENT OFFICE.

PETER G. JACOBSON, OF CHICAGO, ILLINOIS.

RAZOR-BLADE HOLDER.

1,318,278.

Specification of Letters Patent.

Patented Oct. 7, 1919.

Application filed February 8, 1917, Serial No. 147,291. Renewed March 6, 1919. Serial No. 281,072.

To all whom it may concern:

Be it known that I, PETER G. JACOBSON, citizen of the United States, residing at Chicago, in the county of Cook and State 5 of Illinois, have invented a certain new and useful Improvement in Razor-Blade Holders, of which the following is a full, clear, concise, and exact description.

My invention relates to razor blade holders and is of particular service in the formation of holders to be used in holding the blades that are to be honed, though the invention is not to be limited to this use.

My invention has for one of its objects 15 the provision of improved means for limiting the extent to which the blade holding clamp may swing with reference to the handle carrying it. I employ a motion limiting connection engaging both the handle and the clamp.

My invention has for another of its objects the provision of improved mechanism for forcing the jaws of the blade holding clamp into engagement with the blade to 25 be held thereby and to this end I employ transverse continuations upon the jaws and means acting upon these continuations for the purpose stated.

I will explain my invention more fully 30 by reference to the accompanying drawing showing the preferred embodiment thereof and in which Figure 1 is a view in side elevation of a razor blade holder as I preferably make it; Fig. 2 is a plan view; Fig. 3 is a view on line 3—3 of Fig. 2; Fig. 4 is a 35 view similar to Fig. 3 but with the jaws of the blade holding clamp open; Fig. 5 is a view on line 5—5 of Fig. 3; Fig. 6 is a view on line 6—6 of Fig. 4; and Fig. 7 is 40 a view on line 7—7 of Fig. 5.

Like parts are indicated by similar characters of reference throughout the different figures.

The blade holder includes one member in 45 the form of a blade holding clamp having jaws 1, 1 and a second member in the form of a handle 2 upon which the clamp is mounted between its front blade holding end and its rear end to swing upon the handle. The handle has forked branches 3 carrying a clamp supporting rod at their forward ends. This rod is preferably of sectional formation, its parts being a sleeve 4 and trunnion screws 5 and 6 entering the 50 bore of the sleeve and in threaded connection with the ends thereof. Each of the

jaws has transverse continuations 7, the transverse continuations upon one jaw being interposed between the transverse continuations upon the other jaw. The tube or 60 sleeve 4 is interposed between the continuations upon one jaw and has butt engagement with said continuations. The trunnion screws extend outwardly beyond the clamp and their stems are surrounded by said continuations and the forward ends of the fork branches 3 of the handle, whereby the clamp and handle are assembled and the clamp may swing upon the handle at a point between the forward and rear ends of the 70 clamp.

The rear ends of the clamp jaws are pivotally united by a shaft 8 passing therethrough and which shaft carries a roller 9 for supporting the clamp in proper position 75 upon the hone. The extent to which the clamp may swing upon the handle is limited by the connections 10 that are continuations of the shaft 8 and whose outer ends have lost motion engagement with the handle 80 parts 3, preferably by operating in slots 11. When this construction is adopted, the shaft 8 is desirably made in two parts as indicated in Fig. 5.

The openings in the jaw continuations 85 through which the trunnion screws 5 pass are preferably in the form of slots extending longitudinally of the clamp and along which said screws may be moved bodily and longitudinally with reference to the clamp. 90 This may be done by holding the clamp in one hand and the handle in the other and moving the clamp toward or away from the handle. When the clamp is pulled out as far as possible, the screws are at the rear 95 of the slots (Fig. 4) and these slots are then most out of register and the jaws of the clamp are then farthest apart to permit of the insertion of a blade 12. When the screws are forced to the front ends of the 100 slots, the slots are brought more into register and the jaws are consequently forced together (Fig. 3) to grip the inserted blade 12. The front end of one of the slots is continued laterally of the slot in one direction 105 and the front end of the other slot is continued laterally in an opposite direction whereby a locking formation is produced to hold the shaft when the blade is clamped, the shaft being prevented from working 110 backward. The rear ends of the slots may be similarly curled to cause the shaft to

be held when the jaws are separated but such formation of the rear ends of the slots is not essential. The jaws are resilient and are therefore firmly applied to the blade.

5 Claims relating to the jaws and the means co-acting therewith for forcing the jaws together are made in a division of this application, the divisional application having been filed March 28, 1918, under Serial No.

10 225,230.

While I have herein shown and particularly described the preferred embodiment of my invention I do not wish to be limited to the precise details of construction shown 15 as changes may readily be made without departing from the spirit of my invention, but having thus described my invention I claim as new and desire to secure by Letters Patent the following:—

20 1. A safety razor blade holder including a clamp that is adapted to hold a razor blade at its front end; a handle upon which the clamp is mounted between its front blade holding end and its rear end to swing upon the handle; and a motion limiting connection movable with respect to and engaging both the handle and the part of the clamp to the rear of its mounting to limit the swinging movement of the clamp with respect to the handle.

25 2. A safety razor blade holder including one member in the form of a clamp that is adapted to hold a razor blade at its front end; a second member in the form of a handle upon which the clamp is mounted between its front blade holding end and its rear end to swing upon the handle; and

a motion limiting connection between the handle and the part of the clamp to the rear of its mounting and carried by one of said members and engageable with the other member and having lost motion with respect thereto, whereby swinging movement of the clamp with respect to the handle is permitted and limited.

45 3. A safety razor blade holder including a clamp that is adapted to hold a razor blade at its front end; a handle upon which the clamp is mounted between its front blade holding end and its rear end to swing upon the handle; and a motion limiting connection carried by the clamp and engageable with the handle and having lost motion with respect thereto whereby swinging movement of the clamp with respect to the handle is permitted and limited.

50 4. A safety razor blade holder including a clamp that is adapted to hold a razor blade at its front end; a handle upon which the clamp is mounted between its front blade holding end and its rear end to swing upon the handle; a motion limiting connection carried by the clamp and engageable with the handle and having lost motion with respect thereto whereby swinging movement of the clamp with respect to the handle is permitted and limited; and a roller at the 55 rear end of the clamp and carried by said connection.

55 In witness whereof I hereunto subscribe my name this first day of February, A. D. 1917.

70 PETER G. JACOBSON.
